UNITED STATES PATENT OFFICE.

CHARLES L. CHISHOLM, OF MARYSVILLE, NEW BRUNSWICK, CANADA, ASSIGNOR TO
CHISHOLM TRANSMITTER & TELEPHONE INSTRUMENTS COMPANY.

TELEPHONE SYSTEM AND INDIVIDUAL TRANSMITTER THEREFOR.

1,158,636.

Specification of Letters Patent.

Patented Nov. 2, 1915.

Original application filed March 21, 1910, Serial No. 550,624. Divided and this application filed June 15, 1910. Serial No. 567,007.

To all whom it may concern:

Be it known that I, CHARLES L. CHISHOLM, a citizen of the United States, residing at Marysville, in the Province of New Brunswick, Canada, have invented a new and useful Telephone System and Individual Transmitter Therefor, of which the following is a specification.

This invention has reference to improvements in individual telephone transmitters and its object is to provide a telephone transmitter which may be individual to the user, the transmitter being portable and readily attachable to and detachable from freely accessible circuit terminals of transmitter circuits situated at local stations in the telephone system, which local stations are each provided with a receiver local thereto and may or may not be also provided with a transmitter local to the station.

In ordinary telephone stations of a public or semi-public character there is constant danger of infection of healthy persons with diseases due to the use of the telephone and especially of the transmitters by persons already having diseases. The transmitter is particularly liable to become infected through being used by diseased persons because of the deposition of moisture in the mouth piece of the transmitter and upon the diaphragm during the act of speaking thereto, and disease germs find ready lodgment in the mouth piece already moistened and warmed by use, and upon the diaphragm likewise moistened and warmed. The condition for the propagation of disease germs is particularly favorable in the chamber immediately adjacent to the diaphragm of telephone transmitters in ordinary use, and when the moisture has evaporated such germs are readily dislodged and may easily reach the mouth and nose of a subsequent user so that a public or semi-public station is, because of the transmitter, a constant menace to users of the telephone.

Various means have been proposed for eliminating the danger of disease infection on the transmitter side of the telephone unit and such means usually consist either of protecting devices for the mouth piece to be removed and destroyed after each use of the telephone, or a constantly present disin-

fectant, or some other like expedient, or an attendant is charged with the duty of cleansing and disinfecting the telephone receiver after each use. The removable mouth piece protector is more or less of a nuisance to the user and for this purpose the employment of such a protector is often neglected, and furthermore such mouth piece protectors do not prevent the accumulation of disease germs on the diaphragm. If a germ proof shield be employed it interferes with the proper transmission of the sound waves to the diaphragm. The constant presence of a disinfectant is usually highly disagreeable to the user of the telephone. An attendant is often neglectful, and seldom if ever attempts to cleanse the diaphragm, such diaphragm usually being out of reach.

The desirability of individualizing telephones has long been recognized, both for sanitary reasons and because many persons of refined tastes object to promiscuously used public telephones, but attempts to individualize the telephone have at best only resulted in the production of bulky instruments too large to be readily stored or transported by the ordinary user, and furthermore requiring marked changes in existing telephone installations.

By the present invention the transmitter only is individualized to the user for it is the transmitter that is practically the sole source of danger in the use of public telephones, since the danger from the receiver is almost wholly negligible.

By the present invention the transmitter is made of minute size and coacting parts are so related thereto that the transmitter, the mouth piece, and a protecting casing for these parts for permitting the instrument to be readily carried in the pocket, do not necessarily exceed the size of an ordinary watch of medium diameter and thickness so that the whole instrument is well adapted to a vest pocket.

The present invention contemplates not only the features mentioned but other features, resulting in the elimination not only of all the dangers to the health of the users of telephones but of all of the disagreeable features of public or semi-public telephones,

all of which will be best understood from a consideration of the following detailed description taken in connection with the accompanying drawings, in which drawings:—

Figure 1 is a diametric section, with parts in elevation of an individual transmitter as housed in a casing similar to a watch casing, the showing being on a somewhat enlarged scale. Fig. 2 is a view similar to that of Fig. 1 but showing the casing open and the mouth piece of the transmitter in the operative position. Fig. 3 is a section of the structure of Fig. 1 on a diameter approximately at right angles to the diameter of the section of Fig. 1. Fig. 4 is a view showing the individual transmitter without the protecting casing and with a non-collapsible mouth piece, the latter being shown in section. Fig. 5 is an elevation of a desk set showing the adaptability of the individual transmitter thereto. Fig. 6 is a section, on an enlarged scale of circuit terminals used in connection with the present invention. Fig. 7 is a section, on an enlarged scale, of the terminal carrying portion of the individual transmitter, such terminals being adapted to the local station terminals illustrated in Fig. 6. Fig. 8 is a diagram of a telephone system showing local stations suitably equipped for the use of the individual transmitter. Fig. 9 is an enlarged detail view of a portion of the individual transmitter, with parts in section.

Referring to the drawings and more particularly to Figs. 1, 2 and 3 there is shown a casing 1 provided with a cover 2 which may or may not be hinged to the body of the casing but which is shown in the drawings as so hinged, and the casing with its cover is in size and shape similar to an ordinary watch case, whereby the structure, when closed, is adapted to be placed in the vest pocket if desired, thus making the transmitter highly convenient for individual use.

Mounted in the casing 1 is a transmitter element 3 which may be considered as a granular microphonic element of minute size with the diaphragm and granule chamber substantially coextensive, the sound receiving diaphragm being of less diameter than the diameter of the bell end of mouth pieces such as are commonly employed in connection with transmitters.

The microphonic element 3 is mounted in the casing 1 between the back thereof and a plate 4 which may overlie in part the diaphragm of the transmitter to form a shallow air chamber. It will be understood however that the plate 4 is not absolutely necessary since the microphonic element may be mounted directly on the inner back wall of the casing 1.

Secured to the transmitter element 3 or to

the plate 4 where constituting the outer covering for the transmitter element is a mouth piece 5 which may be screwed or otherwise secured to a boss 6 formed on the front of the plate 4 and having a passage therethrough so that sound waves may easily reach the diaphragm in the usual manner.

In order that the transmitter may be readily portable and convenient to the user it is preferred to form the mouth piece 5 in such manner as to be easily collapsible and for this purpose it may be made of a spiral wire 7 having a constant tendency toward the expanded position but which may be collapsed in the direction of the axis of generation of the spiral, and this spiral wire support 7 is provided with a covering 8 of some suitable flexible material which for the best results should be impervious to moisture. Soft rubber, oiled silk, and like materials are adapted for this purpose.

The mouth piece 5 may remain on the transmitter and when the cover 2 is closed onto the body portion 1 of the casing then this mouth piece will collapse into very shallow space, but by forming the wire 7 of elastic metal, such for instance as piano wire, the mouth piece will have a constant tendency to assume the operative or expanded position. The casing 1 may be provided with a catch 9, push piece 10, and ring 11 similar to like parts in watch cases so that when the cover is closed down on the body portion 1 it will be locked in this position but may be readily released by pressure on the push piece 10 and the cover will then move to the open position either under the action of a spring such as is commonly used in watch cases, or by the expansive impulse of the mouth piece 5. The ring 11 forms a ready means for attaching the casing to a watch chain or other fastening device so that the user may carry the device in the pocket without danger of losing it, in the same manner as a watch is carried. The flexible covering of the spiral wire 7 may either be inside the spiral or outside the same, or the spiral may be housed in such covering.

In the particular structure shown in the drawings there is mounted in the casing 1, between the back of the casing and the plate 4, a block 12 of insulating material having spaced cavities 13 matching spaced openings 14 through the rim of the casing at any convenient point therearound, but preferably located with reference to the push piece 10 in either the six o'clock position or the twelve o'clock position, considering a watch face as usually mounted in a watch casing.

Centralized in the sockets 13 of the block 12 are pins 15 of conducting material and these pins are connected by suitable conductors 16 to the respective electrodes of the microphonic element. The pins 15 therefore

constitute the terminals of the microphone element which terminals are local to the individual transmitter. The terminals 13 are preferably within the confines of the casing 1 so that there is no obtrusive projection beyond the casing.

In order to adapt existing telephone systems already installed, or new installations, for the use of the individual transmitters, some modification of such systems is necessary, but where telephone stations are already installed with receivers and transmitters, the transmitters already in place need not be disturbed and provision may be made whereby the individual transmitter may be used, if desired, or the transmitters already installed may be used, each without interference from the other.

A telephone system embodying the present invention is illustrated in Fig. 8, where there is indicated a central station 17 with telephone line conductors 18 extending therefrom to various local stations, two of which latter are indicated as sufficient to illustrate the system of this invention. The convenience of description one of these local stations is designated 19 and the other 20. Each station contains a receiver 21 local thereto. At the station 19 there is installed a transmitter 22 local to this station, and at the station 20 the transmitter itself is omitted but the transmitter circuit is retained.

At station 19 the continuity of the transmitter circuit may be readily broken at one point and another circuit established around the transmitter 22 to circuit terminals 22, 23 this new circuit including the primary of the usual induction coil 25 and the charging battery 26 or other charging source for the transmitter circuit at the local station.

In the arrangement shown at station 19 a conductor 27 is branched to the terminal 23 and a conductor 28 is branched to the terminal 24 and when these terminals are bridged, provision is made for cutting out the transmitter 22. A terminal structure adapted for the conditions present at station 19 is illustrated more in detail in Fig. 12 of an individual transmitter, the plugs 30 being made elastic by splitting as indicated at 31 or constructed in any other manner to readily lock in the passages 13 without binding therein too firmly to interfere with ready removal of the plugs 30 when desirable. Each plug 30 has a metal tubular lining or sleeve 32 which may be also split to render it elastic and this metal lining 32 is designed to receive a corresponding pin 15 constituting a circuit terminal of an individual transmitter. The other end

of the sleeve 32 from that entering a plug 30 may receive a metal plug 33 to which may be soldered or otherwise secured the respective conductors 27 or 28 as the case may be. The end of the sleeve 32 within the plug 30 stops short of the outer end of the plug so that accidental contact therewith is prevented.

Under the conditions present at local station 19 one of the sleeves 32 is in electrical connection with a plate or strip 34 traversed by the stem 35 of a plug 36 movable in a passage 37 formed in the block 29 in spaced relation to that plug 30, the conducting sleeve 32 of which is connected to the conducting plate or strip 34. The end of the stem 35 projecting through the plate or strip 34 carries a conducting plate 38 to which there is secured a conductor 39 leading to one side of the transmitter 22. A spring 40 housed within the passage 37 serves to maintain the block 36 in a projected position but this spring will permit the block 36 to move into the passage 37 on the application of sufficient force to compress the spring 39, and this will move the plate 38 out of contact with the plate 34, but under normal conditions electrical contact is maintained between these two plates.

The conductors 28 and 39 constitute portions of the local transmitter circuit at station 19 and this circuit is normally maintained at the plates 34 and 38 by the action of the spring 40 and when the block 36 is disengaged the telephone transmitter 22 may be utilized in the usual manner. If however the block 36 be moved against the action of the spring 40 then the telephone transmitter 22 is cut out of the local transmitter circuit.

In an arrangement such as shown at local station 19 of the system of Fig. 8, if an individual transmitter be applied to the terminals 23 and 24 by the introduction of the plugs 30 into the sockets 13, then on the seating of the plugs 30 in said sockets the block 36 is brought into contact with the plate 34 and the spring 40 is compressed thus cutting out the transmitter local to the local station 19 by the act of including the individual transmitter in the transmitter circuit at said station. Under the circumstances assumed it will be seen that either the transmitter local to the station or the individual transmitter may be used as may be desired. This is particularly valuable in semi-public stations where the use of the transmitter there located may be confined to one or more authorized persons while the more general use of the station will be possible for persons supplied with the individual transmitters. By this means the danger of contaminating the transmitter or of transmitting diseases is reduced to a negligible minimum.

Where it is not desirable to have a tele-

15 to the right, and a circuit before at 20 a local telephone system mechanism is formed of the terminals 24 and 25, the sound receiving and telephone transmitter 26, and an individual transmitter circuit is received together with the readily accessible terminals 23 and 24 adapted 25 to be inserted in the sockets 13 to complete the circuit to the individual transmitter. The microphone is passed through the pins 26. This arrangement is shown at station 30 26 in Fig. 3. At this local station 29 the transmitter 26 is indicated as forming a local telephone, it will be understood 35 that the individual transmitter 26 will not be used in connection with the local telephone.

30 At another station, a desk set 41 having a desk 42, a block 43 of terminals 28-31, a telephone handset, and an individual transmitter 26, it may be readily applied 35 to the desk set. The circuit terminals 28-31 are secured to a board of tools, this facilitating the removal and removal 40 of the individual transmitter from the readily accessible terminals 28-31 of the transmitter, carrying the telephone handset, whatever 45 tools are used, and together with the ready portability of the individual transmitter and its transmitter 26 whereby it is 50 adapted to small pockets such as vest pockets greatly enhances the usefulness of the individual transmitter.

55 Where the collapsibility of the mouth piece 3 is not of prime importance, a non-collapsible mouth piece 42, shown in Fig. 4, may be applied to the transmitter 3 and the latter may replace the transmitter 22 of station 19 or may be used as an individual transmitter to be removed from the readily 60 accessible transmitter circuit terminals and secured away when not in use to prevent 65 other persons from using the particular individual transmitter.

70 In order to provide for the ready cleaning 75 of the individual transmitter, the individual transmitter is provided with a plug 76 imbedded in a granule chamber 77, this plug 78 is in the form of a safety telephone screw plug 79.

80 A feature of the invention, the importance 85 of which is particularly described, is in 86 the individual transmitter, consisting of the mouth 90 piece, does not require the use of other circuit 95 terminals and other means for connecting 100 the individual telephone transmitter into a telephone system, whether the local 105 transmitter be present or not, this coupling 110 of the individual transmitter into the circuit 115 being possible without the aid of tools 120 and wires.

125 The individual transmitter being of small 130 size and of such a size as to be readily 135 carried about and used in public places, 140 such as the telephone booth.

145 The individual transmitter, like all

150 individual transmitter is due to its being 155 sanitary and thereby preventing the 160 spreading of centers of infection and the 165 spread of disease, for the use of the transmitter 170 is confined to one individual. The 175 invention is particularly useful in connection 180 with telephones installed in hospitals or 185 hotels, or public telephone booths or any other public or semi-public place. Persons 190 affected with diseases liable to be transmitted 195 can with the individual transmitter 200 readily use telephones and have the satisfaction 205 of knowing that such use is free from the liability of endangering others. The 210 same cleanliness of the individual transmitter 215 renders it will present a welcome relief 220 to those who object from cleanly motives to the indiscriminate use of telephones.

225 It is also another advantage of the individual transmitter which however is commercial rather than sanitary. By the employment 230 of the individual transmitter the indiscriminate use of the telephone by non-subscribers is prevented since telephone systems 235 called for use with the individual transmitter 240 only could not be used by others and for every purpose for which the individual transmitter is provided would prevent 245 being loaned by the owner to others.

250 The particular construction of the 255 metallic side of the individual transmitter 260 of this invention does not enter into the present invention, it may be stated that the transmitter, including the sound receiving 265 granule and the granule chamber, may be less than one inch in diameter and less 270 than three sixteenths of an inch in thickness and the casing inclosing the transmitter 275 need only be sufficiently large to accommodate the mouth piece when in the collapsed 280 condition and since the open end of such mouth piece has been found in practice to operate successfully when of less diameter than mouth pieces in common use, the entire 285 structure need not exceed the size of a 290 man's size watch of thin model.

295 The application is a division of my application for improvements in telephone systems and individual transmitters, therefore filed March 21, 1910 under Serial No. 1,053,630.

300 What is claimed is:

305 A portable telephone transmitter having 310 circuit terminals local thereto, and provided 315 with a collapsible mouth piece, and a two part 320 casing, one part of which has the transmitter and its terminals secured thereto, and the other part of which constitutes 325 a cover for the first part of the casing, said 330 casing when closed housing the transmitter and the mouth piece in the collapsed position, and the mouth piece when the casing is 335 being removed to the operative position.

340 A portable telephone transmitter having 345 circuit terminals local thereto and pro-

vided with a collapsible mouth piece, a two-part casing one part of which has the transmitter and its terminals secured thereto and the other part of which is hinged to and 5 constitutes a cover for the first part of the casing, said casing when closed housing the transmitter and its mouth piece in collapsed position.

3. A telephone transmitter provided with 10 a casing having a cover and a collapsible mouth piece, both mouth piece and cover tending normally to open position.

4. A telephone transmitter provided with a casing having a cover and a collapsible 15 mouth piece, the mouth piece being constrained to operative position on the moving of the cover to open position.

5. A portable telephone transmitter comprising a microphonic element, a collapsible 20 mouth piece carried thereby and having a normal tendency to assume open or operative position, a casing adapted when closed to house the telephone transmitter and the mouth piece when the latter is in the collapsed condition, inset circuit terminals for 25 the transmitter carried by the casing, and other circuit terminals at telephone stations adapted to enter the circuit terminals in the casing of the portable transmitter.

30 6. A portable telephone transmitter having circuit terminals local thereto and adapted to be applied to and removed from matching terminals at a telephone station without the aid of tools, a casing for said transmitter 35 formed of two members hinged together, and a mouth piece for the transmitter having a normal tendency to expand to the operative position and collapsible into the casing on the closing together of the latter.

40 7. A portable transmitter comprising a casing provided with a cover, a microphonic element and sound receiving diaphragm therefor included within the confines of the

casing, and a collapsible mouth piece for the transmitter having a normal tendency 45 to assume the operative position and adapted to be housed in the casing in collapsed condition when the cover is closed on the body portion of the casing.

8. A portable telephone transmitter comprising a casing of vest pocket size provided with a cover, both the body of the casing and the cover being constructed of stiff material, a microphonic element and sound receiving diaphragm included within the confines of 55 the casing, and a mouth piece for the transmitter includable within the casing and its cover and movable with respect to the microphonic element and diaphragm to the operative position on the opening of the cover. 60

9. A portable telephone transmitter comprising a casing of vest pocket size provided with a cover, a microphonic element and sound receiving diaphragm included within the confines of the casing, and a collapsible 65 mouth piece for the transmitter includable when collapsed within the casing and its cover and having a normal tendency to assume the operative position.

10. A portable telephone transmitter comprising a casing of vest pocket size provided with a cover, a microphonic element and sound receiving diaphragm included within the confines of the casing, and a mouth piece for the transmitter includable within the 75 casing and its cover and provided with means constraining it toward the operative position on the opening of the cover.

In testimony that I claim the foregoing as my own, I have hereto affixed my signature 80 in the presence of two witnesses.

CHARLES L. CHISHOLM.
